COMBINED HOLDER AND ADVERTISING DISPLAY MOBILE FOR PHONOGRAPH RECORD JACKETS OR THE LIKE

Phillip L. Jacobson, 2353 Canyon Drive,
Los Angeles 28, Calif.

Filed Aug. 15, 1960, Ser. No. 61,757

Term of patent 14 years

(Cl. D80—1)

Fig. 1

Fig. 3Fig. 5*Fig. 7*Fig. 4*Fig. 6*Fig. 8.

FIG. 1 is a perspective view of a combined holder and advertising display mobile for phonograph record jackets or the like embodying my new design;

FIG. 2 is a top plan view thereof;

FIG. 3 is a perspective view of a modified form thereof;

FIG. 4 is a perspective view of another modified form thereof;

FIG. 5 is a perspective view of still another modified form thereof;

FIG. 6 is a perspective view of still another modified form thereof;

FIG. 7 is a top plan view of the form shown in FIG. 4; and

FIG. 8 is an enlarged vertical sectional view taken on line 8-8 of FIG. 6.

I claim:

The ornamental design for a combined holder and advertising display mobile for phonograph record jackets or the like, substantially as shown and described.
